UNITED STATES PATENT OFFICE.

JESSE DE WITT SMITH, OF NEW YORK, N. Y.

AUTOMATIC SWITCH-OPERATING DEVICE.

1,273,282.

Specification of Letters Patent.

Patented July 23, 1918.

Application filed May 8, 1916. Serial No. 96,204.

To all whom it may concern:

Be it known that I, JESSE D. SMITH, a citizen of the United States, residing at New York city, in the county of New York, 5 State of New York, have invented certain new and useful Improvements in Automatic Switch-Operating Devices; and I do hereby declare the following to be a full, clear, and exact description of the invention, such as will enable others skilled in the art to which it appertains to make and use the same.

This invention pertains to the class of automatic switch operating devices, and has 15 particular reference to a switch throwing apparatus for use in connection with street railway systems.

The primary object of my invention is to provide an automatic switch throwing 20 mechanism which will be positive in operation, and which will be constantly set to throw a switch, so as to be always ready for the succeeding car, but which may be allowed to remain inoperative so as to leave 25 the switch in the position in which it is found.

Another object of the invention consists in constructing a switch throwing apparatus which may be operated at will by the 30 motorman of an approaching car, the same operation which throws the switch also acting to reset the other switch operating device.

More particularly, it is the object of my 35 invention to provide a switch throwing apparatus which is composed of few and simple parts, so that its installation may be economically effected and its working parts possess small liability of injury and wearing out, the parts being so arranged that the switch is controlled alternatively by 40 each of a pair of trip devices whose interrelation is such that when one trip device is actuated the other acts as a reset to place 45 the mechanism in condition for a subsequent operation.

With the above, and other objects in view, my invention will now be fully set forth and described, reference being had to the 50 accompanying drawings.

In said drawings:—

Figure 1 is a longitudinal vertical sectional view of the apparatus as arranged below a track,

Fig. 2 is a longitudinal section through 55 a car platform, showing an actuating device carried thereby,

Fig. 3 is a section on line 3—3 of Fig. 1,

Fig. 4 is a section on line 4—4 of Fig. 1, and

60

Fig. 5 is a plan view of a section of track and a switch showing the relationship of the trip device for actuating the switch.

Referring more particularly to said drawings, 1 denotes the frame or casing of a 65 long shallow trench or inclosure which is located between the rails 2, adjacent the switch point 3. Said frame 1 may consist of metal plates and beams of any suitable type and arrangement, and supports upon 70 the upright elements 4 the transverse shafts 5. Said shafts 5 carry the bell crank elements 6, each of the bell crank elements 6 having a downwardly extending arm, but one of said elements lying in the reverse 75 position from that occupied by the other. The downwardly extending arms of the bell crank elements 6 are connected by a link rod 7. The opposite or horizontally 80 extending arms of the bell crank lever 6 are each connected to a vertical shaft 8, the lower ends of the shaft 8 being provided with studs 9 which operate in the horizontally extending slots 10 which are formed in the ends of said horizontally extending 85 arms of the bell crank levers. By reason of the slots 10 any irregularities in the shafts 8 or in the arrangement of the other parts will be taken up. Secured to the upper ends of each of the shafts 8 is a foot 90 plate 11, said foot plates operating in each of the framed openings 12, located in the frame 1 to appear in the street surface, as best noted in Fig. 5.

The arrangement of the above parts is 95 such that when one of the foot plates 11 is depressed the other will be elevated to a position where it can be engaged by the operating device shown in Fig. 4. The operating device shown in Fig. 4 consists of a rotary contact element 13, which has its shaft ends mounted for rotation and vertical movement in the slotted ends of the brackets 14 which are suspended below the platform 15 of a car and are suitably braced at 100 the front and back by means of the brace bar 16. Between the brackets 14, the contact element 13 is journaled in a yoke 17 whose

closed end terminates in a stem 18. Said stem 18 projects through the platform 15 and at its upper end is provided with a head 19. Said head 19 is positioned to be accessible to the motorman, so that he may apply the pressure of a foot thereon to lower the contact wheel 13 to the ground. Interposed between the head 19 and the plate 20 located on the car floor is a coil spring 21 which normally holds the contact wheel 13 in elevated position. Extending in line with the link rod 7, and pivoted to the same arm of one of the bell crank levers 6, is a second link rod 22 whose opposite end is pivoted to a transversely extending arm 23 formed on a vertical shaft 24. Said vertical shaft 24 is pivoted at its lower end in a step bearing 25 carried by the frame, and at its upper end in a bearing 26 which is also mounted on the frame 1. The upper end of the shaft 24 is fixed to the heel of the switch point 3, so that as said shaft 24 is rotated, the switch point will be swung from one position to the other.

The operation of my improved device is obvious from the foregoing; and it might be added that the alternatively acting foot plates 11 provide a constantly set operating mechanism for the switch point, so that regardless of whether a car has thrown the switch so as to leave one of the plates 11 depressed, the motorman of a succeeding car may also operate the switch, by bringing the contact wheel 13 upon his car into operative

contact with the foot plate 11 which is in 35 elevated position.

It is also to be noted that by my improved arrangement, a positive switch throwing device is provided whose parts are simple and comparatively few in number, so that when 40 the device has once been installed, its cost of maintenance should be small and that it should remain in operative condition throughout a long period.

What I claim as my invention is:—

A switch operating device comprising the combination with a track section including a pivoted switch point, of a single casing inset in and extending longitudinally of the track section and having a lateral extension 45 at one end projecting under the heel of the switch point, a shaft depending from the heel of the switch point into said lateral extension, a crank arm on the shaft, transverse shafts supported by the sides of the casing 50 at an intermediate portion and at its end remote from said lateral extension, levers pivoted on said transverse shafts, link connections between said levers and crank arm and lever operating members 55 slidably 60 through the top of the casing and connected with said levers.

In testimony whereof, I affix my signature, in the presence of two witnesses.

JESSE DE WITT SMITH.
